UNITED STATES PATENT OFFICE.

JUSTUS VERSCHIUR, OF JERSEY CITY, NEW JERSEY, ASSIGNOR TO SIMPSON, CRAWFORD & SIMPSON, OF NEW YORK, N. Y.

DESIGN FOR A SPOON.

SPECIFICATION forming part of Design No. 22,195, dated February 7, 1893.

Application filed November 10, 1892. Serial No. 451,563. Term of patent 3½ years.

To all whom it may concern:

Be it known that I, JUSTUS VERSCHUUR, a citizen of the United States, residing at Jersey City, in the county of Hudson and State

5 of New Jersey, have invented and produced a new and original Design for Spoons; and I do hereby declare the following to be a full, clear, and exact description of the invention, such as will enable others skilled in the art to 10 o which it appertains to make and use the same, reference being had to the accompanying drawings, and to letters of reference marked thereon, which form a part of this specification.

15 The figures of the drawings are deemed sufficient but necessary to illustrate the design, Figure 1 being the front, or obverse, view of the design and Fig. 2, a reverse view.

The leading features of the design consist 20 o in a spoon decorated with the figure of a man standing, in a long gown, on a pedestal, the said figure being on or of the handle, and of the bowl, decorated with the representation of the United States Sub-Treasury at Wall 25 street, New York city.

In said drawings, A indicates the broader part of the handle, B the narrow shank thereof and, C the bowl. The concave face of the bowl is decorated with the representation, d, 30 o of the Sub-Treasury building in the city of New York and with spaces e, e, above and be-

low the same. The shank of the spoon, on the front side, is decorated with figures shaped in resemblance to coin f, bills g, and money bags h. The broad extremity of the handle is decorated with a pedestal-like figure, i, on which appears to stand, in cloak or gown and with hand resting on the symbolic fasces, n, a man, l, whose outline gives shape to the extremity of the handle. The reverse side of the spoon 40 presents to view, at the base of the shank, a wreath, j, above this, a longitudinal plane surface on which a panel k appears adapted to receive a suitable inscription, above this again, the pedestal shaped part, and, finally, 45 the standing figure showing the gown more obviously.

What I claim as new is

1. In a design for a spoon, the obverse substantially as shown and described.

2. In a design for a spoon the reverse substantially as shown and described.

3. The design for a spoon, substantially as shown and described.

In testimony that I claim the foregoing I 55 have hereunto set my hand this 1st day of November, 1892.

JUSTUS VERSCHIUR.
